PRESSURIZED PASTE DISPENSERS

Ignatius E. Theodorou, Haverhill, Mass.

Application October 24, 1955, Serial No. 542,159

5 Claims. (Cl. 222—95)

This invention relates to improvements in paste dispensers and more particularly to pressurized paste dispensers wherein fluid under pressure acts to eject the paste.

It has been proposed heretofore to provide pressurized paste dispensers wherein gas under pressure constantly is active tending to eject paste and effective for ejecting the paste whenever the mouth of the dispenser is opened. In some cases, the gas has acted on a piston or plunger which directly engages the paste and which maintains the paste constantly under compression ready to discharge when the mouth of the dispenser is opened. Another variety of prior pressurized paste dispenser has had the paste within a flexible and collapsible container mounted loosely within the main chamber of the dispenser with gas under pressure within the main chamber and constantly tending to squeeze and collapse the paste holding container. Here again the paste is expected to be ejected when the dispenser mouth is opened.

It is among the objects of my present invention to provide a pressurized paste dispenser wherein fluid under pressure is maintained apart from the paste and acts on the paste only periodically and momentarily when the dispenser is manually operated. According to the invention, the paste normally is in a relaxed state in which it assumes a natural position of ease within its container, and ejecting fluid pressure acts upon or is transmitted to the paste only momentarily whenever the dispenser is manually operated.

Another object of the invention is to provide a pressurized paste dispenser wherein the paste and fluid under pressure are in separate compartments of the dispenser, and wherein there is manually operable means for simultaneously opening a fluid passage from the pressure fluid compartment into the paste compartment thereby to effect fluid pressure ejection of paste until the manually operable means is released, there being spring means for restoring said means to its condition closing said fluid passage and for simultaneously venting the paste compartment to atmosphere when the manually operable means is released.

A further object of the invention is to provide a pressurized paste dispenser wherein the paste continues non-toxic within the dispenser for an indefinite period of time.

It is, moreover, my purpose and object generally to improve the structure and effectiveness of pressurized paste dispensers by subjecting the paste to ejecting pressure only momentarily at the desired times of paste ejection.

In the accompanying drawing:

Fig. 1 is a medial cross-sectional view of a paste dispenser embodying features of my invention, a conventional variety of paste tube being shown in elevation;

Fig. 2 is a view generally similar to Fig. 1 but showing the valve means in manually actuated conditions, as when paste is being ejected or dispensed; and

Fig. 3 is a medial cross-sectional view of a modified form of paste dispenser embodying features of my invention.

2

Referring to the drawing, the dispenser 10 may be formed of sheet metal or any other suitable material. Internally, the dispenser is divided by wall 12 to provide two compartments or chambers 14, 16 of which the chamber 14 preferably will have dimensions for accommodating a conventional tube 18 of tooth paste or any other paste or paste-like substance. It should be understood, however, that the paste may be within a tube or other container having any of various shapes and sizes so long as the tube or container walls are of a nature to yield under pressure to eject paste through the outlet passage in neck 20. Also, it should be understood that the features of the invention may be employed in conjunction with the well known plunger or piston principle of ejection, as suggested in Fig. 3.

As represented in Figs. 1-2, the dispenser 10, at one end thereof, has a relatively large opening 22 therein which is closed by the screw-on cap 24. Cap 24 has a central opening for freely accommodating the neck 20 of the tube, and a nut 26 may be screwed exteriorly on neck 20 to secure the tube to the cap 24, preferably with a gasket 28, or other sealing material, interiorly of the cap, for effecting a fluid-tight seal around neck 20 and between cap 24 and the adjacent dispenser walls when the cap is screwed tightly in place.

Fluid under pressure is within compartment or chamber 16, and interior wall 12 has valve means therein whereby pressure fluid from chamber 16 may be admitted to chamber 14 for applying squeezing pressure to the tube 18 when it is desired to eject paste from the tube. As herein represented, the valve means comprises a relatively thick resilient gasket 30, of rubber, or the like, retained in an opening in wall 12, in conjunction with a relatively rigid supporting element 32. A tubular valve member 34 extends slidably through element 32 and gasket 30. Valve member 34 has an enlarged end portion adjacent to gasket 30 with an inclined wall portion 35 providing an opening at 36 into the interior of the tubular valve member 34. A generally similar but reversely arranged enlargement at the other end of valve member 34 has an inclined wall portion 35' providing an opening at 38 into the interior of the valve member 34. A spring 40 engages between element 32 and an abutment 42 on the valve member constantly biasing the latter to its position of Fig. 1 wherein the opening 36 is closed by the gasket 30 sealing the valve member 34 against flow therethrough from chamber 16 to chamber 14. However, when the valve member is moved in direction to uncover the opening 36, gas or other fluid under pressure in chamber 16 can enter the valve member through opening 36, pass longitudinally within the tubular valve member and discharge through opening 38, which always is open, into the chamber 14.

A second valve means is mounted in the lower end wall 44 of the dispenser, as viewed in Figs. 1 and 2. This valve means comprises a relatively thick resilient gasket 46, of rubber, or the like, retained in an opening in wall 44, in conjunction with a relatively rigid supporting element 48. A tubular valve member 50 extends slidably through element 48 and gasket 46 and has shape generally similar to that of the previously described valve member 34. One enlarged end of valve member 50 is located exteriorly of end wall 44 and constitutes a button at 52 which may be actuated by finger pressure to move valve member 50 inwardly of the dispenser. A rigid rod 54 connects the valve members 34, 50 for movement in unison so that a finger actuation of valve member 50 is accompanied by a corresponding actuation of valve member 34.

One of the enlarged end portions of valve member 50 has an inclined surface 51 providing an opening 56 into the interior of the valve member. The other en-

larged end portion of this valve member has an inclined surface 51', adjacent to gasket 46, providing an opening 58 into the interior of the valve member. These two openings 56, 58 normally are open providing a vent passage through valve member 50 from chamber 14 to atmosphere. However, when valve member 50 is manually actuated from its Fig. 1 position to its Fig. 2 position, opening 56 becomes sealed by gasket 46 and remains sealed as long as valve member 50 is manually held in its Fig. 2 position. Simultaneously, the other valve member 34 moves to uncover the opening 36 within chamber 16 and pressure fluid is admitted through valve member 34 into chamber 14 from chamber 16, to apply squeezing pressure to the paste container and a resulting ejection of paste through neck 20. As soon as valve member 50 is released, spring 40 restores the valve members to their Fig. 1 positions in which opening 36 is closed, cutting off flow between the chambers, and openings 56, 58 are open for venting chamber 14 to atmosphere.

Any suitable readily openable cap 60 may be provided for the paste container opening in neck 20.

Fig. 3 shows a modification wherein the paste is directly held within a cylinder chamber 14' of the dispenser, with a piston member 62 adapted to engage the paste and eject it from the opening in neck 20' in response to actuation of button 52. The valve means in Fig. 3 may be the same as in Figs. 1 and 2 excepting that the piston member responds to actuation of button 52 to force paste through neck 20' by means of pressure fluid from chamber 16'.

It will be obvious from the foregoing description, in connection with the drawing, that I have provided a pressurized paste dispenser wherein gas or other fluid under pressure is transmitted to the paste only momentarily at times of actuation of button 52. At all other times, atmospheric pressure prevails around the paste container 18 in the Figs. 1 and 2 embodiment, and on the piston member 62 in the Fig. 3 embodiment. Hence, the paste during periods between actuations of button 52 is in a natural un-pressurized condition of ease within its container ready for effective response to ejecting pressure. Also, by relieving the paste of constant substantial pressure, the paste-ejecting gas or other fluid under pressure does not penetrate through the container wall material or seep past the piston member 62. Hence, the paste continues indefinitely in a non-toxic condition within the dispenser, which makes it feasible to dispense food in paste form, and various other paste materials which must be maintained in a non-toxic condition.

Various changes in details of the disclosed dispensers may be made within the scope of the appended claims, and it is intended that the patent shall cover, by suitable expression in the appended claims, whatever features of patentable novelty exist in the invention disclosed.

I claim as my invention:

1. A paste dispenser comprising walls defining a fluid pressure chamber and a chamber for holding a supply of material in paste form, means defining an outlet in a wall portion of said paste holding chamber, valve means operable to open a passage for flow of fluid under pressure from said fluid pressure chamber into paste-ejecting relation to the paste in said paste holding chamber, resilient means constantly biasing said valve means to a position in which it closes said flow passage, manually operable means connected to said valve means for actuating said valve means in opposition to its said bias thereby to open said flow passage, and means for venting said paste holding chamber to atmosphere in response to each movement of said valve means to its position closing said flow passage.

2. A paste dispenser comprising walls defining a fluid

pressure chamber and a chamber for holding a supply of material in paste form, means defining an outlet in a wall portion of said paste holding chamber, valve means including one valve element movable between a position in which it seals the dispenser against flow of pressure fluid between said chambers and a position in which fluid under pressure can flow from said fluid pressure chamber into said paste holding chamber thereby to eject paste through said outlet, said valve means also including a second valve element rigidly connected to said one valve element and arranged and adapted to effect venting of said paste holding chamber to atmosphere whenever said flow passage is sealed and to seal said paste holding chamber against outflow of pressure fluid therefrom whenever said flow passage is open.

3. A paste dispenser comprising walls defining a fluid pressure chamber and an adjacent chamber for holding a compressible container of paste, means providing an outlet passage through which paste may be ejected from said container and the chamber in which the container is held, manually operable valve means movable to release pressure fluid from the fluid chamber into said adjacent chamber whereby the released fluid under pressure squeezes said paste container to eject paste through said outlet passage, a spring constantly biasing said valve means to a position in which it seals said fluid pressure chamber against flow of pressure fluid therefrom into said adjacent chamber, and means responsive to operations of said valve means for venting said adjacent chamber to atmosphere whenever said fluid pressure chamber is sealed against outflow and for sealing said adjacent chamber against outflow of pressure fluid therefrom whenever said valve means is operated to release pressure fluid from said fluid pressure chamber into said adjacent chamber.

4. A paste dispenser comprising a closed receptacle, a compressible container of fluid material supported within said receptacle and having an outlet passage extending through a wall portion of the receptacle, means defining an inflow passage for inflow of pressure fluid to the interior of said receptacle, means defining a venting passage leading out of said receptacle, unitary manually operable means controlling said passages and movable in one direction for simultaneously opening said inflow passage and closing said venting passage thereby to subject said container to material-ejecting fluid pressure within said receptacle while said receptacle is sealed against escape of pressure fluid therefrom, and movable in the opposite direction for simultaneously closing said inflow passage and opening said venting passage thereby to relieve said container of material-ejecting pressure.

5. A dispenser comprising walls defining a fluid pressure chamber and a chamber for holding a supply of material in a fluid state, means defining an outlet in a wall portion of said material-holding chamber, valve means operable to open a passage for flow of fluid under pressure from said fluid pressure chamber into material-ejecting relation to the material in said material-holding chamber, resilient means constantly biasing said valve means to a position in which it closes said flow passage, manually operable means connected to said valve means for actuating said valve means in opposition to its said bias thereby to open said flow passage, and means for venting said material-holding chamber to atmosphere in response to each movement of said valve means to its position closing said flow passage.
